UNITED STATES PATENT OFFICE

2,651,130

DECORATIVE TREE

Louis C. Stratmann, Jr., New Orleans, La.

Application August 15, 1950, Serial No. 179,601

2 Claims. (Cl. 41—15)

1

This invention relates to improvements in decorative articles.

An object of this invention is to provide an ornamental artificial tree adapted to be used whenever found desirable, as during the Christmas season, Easter time and for other occasions, the tree being made of a single piece of bendable material in sheet form and stamped or otherwise cut in order to provide a base with a trunk rising therefrom, the trunk being arranged with a longitudinal crease therein for rigidity of construction and the trunk having laterally projecting branches or arms extending therefrom which may be easily bent and twisted to the desired shapes.

Ancillary objects and features of importance will become apparent in following the description of the illustrated form of the invention.

In the drawing:

Figure 1 is a perspective view of the device;

Figure 2 is a plan view of the blank from which the device was made;

Figure 3 is a fragmentary perspective view of a part of one of the branches, and;

Figure 4 is fragmentary sectional view which is presented to show that the trunk has a longitudinal indentation therein for strength of construction.

Briefly summarized, one phase of the invention has to do with the finished or ready-to-use ornamental tree in Fig. 1 and the other phase has to do with what is considered to be a novel new article of manufacture; namely, a blank of malleable metal stamped out from a larger sheet and comprising a flat discoidal portion adapted to serve as a self-standing base, a larger trapezoidal portion integrated with said discoidal portion by way of a complementary struck-out tongue of predetermined delineation, the lengthwise median portion of said trapezoidal portion being imperforate and indented from end to end by a linearly straight indentation, the remainder of said trapezoidal portion being formed with spaced parallel slits defining tines which are susceptible of being transformed into deformable limbs, the outer ends of said tines being obliquely cut to define sharp-pointed impaling prongs.

In carrying out this invention there is provided a blank generally indicated as 10 which is made of a single piece construction. Many materials of construction may be employed the preferable one being aluminum in as much as it is sufficiently malleable to serve the purpose and yet rigid enough to hold its shape after once having been formed.

2

The blank is cut, as by stamping so that a base 10 is formed with a slot 12 therein, part of the material 14 from which the slot was made being slightly bowed at its sides and forming the lower part of the trunk section or trunk 16 of the tree.

This trunk has a longitudinal crease 18 formed therein for rigidity of construction and has a plurality of laterally extending branches 20 integral therewith. These branches are divided by means of cuts and are of graduated sizes, the smaller (in length) branches being near the top of the tree, while the longer ones are near the bottom thereof. The ends of the branches are preferably pointed as at 22 to form a means of supporting various confections 24 which may be marshmallows, Christmas candies, fruit or others.

In practice the blank 10 is formed, as by a single stamping operation. Then the trunk 16 is bent upwardly at the fold line 26 in the base 10.

The trunk is then in a vertical position, while the base 10 is horizontal for disposition on any support, as a table. Each of the branches are then bent and twisted as at 28 (Figure 3) in order to form the branches 20. The actual bending is left within the prerogative of the user, depending upon the location at which the tree is to be disposed. In other words, if the tree is to be disposed in a corner, substantially all of the branches may be formed so that they extend forwardly. If the tree is to be displayed at a location where it is to be visible completely around it, some of the branches may be bent so that the complete appearance of the tree is obtained.

When it is desired to store the tree, it is necessary only to again fold the base 10 with respect to the trunk 16 on the fold line 26 and flatten the branches 20 slightly so that they assume a general, but not completely, planar configuration.

Having described the invention, what is claimed as new is:

1. A knockdown ornamental tree for festive occasions adapted to be manufactured and sold wholly in flat ready-to-use form comprising a flat circular self-standing base, a trunk having an enlarged basal portion integral with said base, said trunk rising perpendicularly from said base and the major portion thereof being indented lengthwise and providing a portion which is V-shaped in cross-section, and a plurality of complementary limbs integral with and extending laterally from the respective longitudinal edge portions of said trunk, said limbs being of a readily deformable shape-sustaining malleable material which is manually bendable, whereby said limbs may be transformed from flat form

to variegated decorative forms representing branches, said basal portion of said trunk being a complement of and struck out from said base and also bent up from said base.

2. As a new article of manufacture, a blank of malleable metal stamped out from a larger sheet and comprising a flat discoidal portion adapted to serve as a self-standing base, a larger trapezoidal portion integrated with said discoidal portion by way of a complementary struck-out tongue 10 of predetermined delineation, said trapezoidal portion being coplanar with said discoidal portion, the lengthwise median portion of said trapezoidal portion being imperforate and indented 15 from end to end by a linearly straight indenta-

tion, the remainder of said trapezoidal portion being formed with spaced parallel slits defining tines which are susceptible of being transformed into deformable limbs, the outer ends of said tines being obliquely cut to define sharp-pointed impaling prongs.
